METAL SPRAYING APPARATUS

Thomas G. Valentine and Edward J. Brennan,
San Diego, Calif.

Application May 12, 1934, Serial No. 725,370

3 Claims. (Cl. 91—12.2)

Our invention relates to a metal spraying apparatus, in particular to an apparatus for melting metal in the form of a wire or rod by means of acetylene and oxygen and spraying it by air pressure upon metal surfaces for building up such surfaces, and the objects of our invention are:

First, to provide a nozzle for such spraying apparatus in which there is no leakage of air into the acetylene or other fuel but the air and fuel are kept separate;

Second, to provide an apparatus of this class with single piece tips and a single locking nut, thus minimizing any chance of leakage; and

Third, to provide an apparatus of this class which is simple and economical of construction, durable, efficient in its action, and which will not readily deteriorate or get out of order.

With these and other objects in view as will appear hereinafter, our invention consists of certain novel features of construction, combination and arrangement of parts and portions as will be hereinafter described in detail and particularly set forth in the appended claims, reference being had to the accompanying drawings and to the characters of reference theron which form a part of this application, in which:

Figure 1 is a central longitudinal sectional elevational view of our apparatus shown fragmentarily showing some of the parts in elevation to facilitate the illustration; Fig. 2 is a transverse sectional view through 2—2 of Fig. 1 and showing some of the parts and portions in elevation to facilitate the illustration; Fig. 3 is a fragmentary sectional view on an enlarged scale substantially along the line 3—3 of Fig. 1 but showing the member 16 in end elevation; Fig. 4 is a sectional view on an enlarged scale along the line 4—4 of Fig. 1; Fig. 5 is a sectional view along the line 5—5 of Fig. 1, and Fig. 6 is a diagrammatical greatly enlarged longitudinal sectional view of a fragmentary portion of the nozzle of our apparatus.

Similar characters of reference refer to similar parts and portions throughout the several views of the drawings.

The gear box 1, flexible shaft 2, wire guides 3 and 4, knurled feed roll members 5 and 6, journal members 7, springs 8, casings 9, adjusting bolts 10, shaft 11, worm gear 12, worm pinion 13, manifold 14, hood 15, nozzle member 16, nozzle cap 17, apparatus support 18, fuel conductor 19, and air conductor 20, constitute the principal parts and portions of our metal spraying apparatus.

The gear box 1 is hollow and rectangular in

shape, as shown best in Figs. 1 and 2 of the drawings. It is provided with a cap 1a on its upper side which is secured thereon by bolts or otherwise. It is provided on one side with an extended lug 1b which is adapted to receive the journal 2a for the flexible shaft 2. This flexible shaft 2 is adapted to extend to any prime mover preferably a variable speed motor to which it is connected. At the other end the shaft is extended by means of a shaft 2b upon which is mounted a worm pinion 13 which meshes with a worm gear 12, which worm gear 12 is secured to the shaft 11. This shaft 11 is journaled in the box 1 by means of journals 11a and 11b at its opposite ends.

Mounted on this shaft 11 is the feed roll member 5 which has flanges at its sides, as shown best in Fig. 2 of the drawings, and directly connected with this feed roll member 5 is a spur gear 5a both of which are secured to the shaft 11 and revolve therewith. Meshing with this spur gear 5a is another spur gear 6a which is connected with the feed roll member 6, as shown best in Fig. 2 of the drawings. The feed roll member 6 is an unflanged roll and is adapted to roll inside of the flanges of the roll member 5 and their peripheries are spaced to permit the wire or rod W to pass between.

The members 6 and 6a are mounted on a shaft to which they are secured and the extended ends of said shafts are journaled in the journal members 7 and these journal members 7 extend upwardly through the upward side of the box 1 and are supported in casings 9, the upper ends of which are internally threaded and in which are mounted the adjusting bolts 10 which engage the upper ends of springs 8 which are positioned between the adjusting bolts 10 and shoulders on the members 7, and are adapted to move them downwardly so that the roll member 6 engages the wire or rod W and provides proper adjustment of the rolls relatively to said wire.

In the one side of the box 1 is an opening 1b which is provided with a flange 1c surrounding the same. Within this opening 1b is supported a manifold 14 by means of an annular lug 14a which extends into said opening and is secured in position by means of set screws through the flange 1c and against the portion 14a. This manifold extends downwardly and outwardly from the casing, as shown best in Figs. 1 and 5 of the drawings, and is provided with air conducting bores 14b which extend upwardly, as shown best in Fig. 5 of the drawings, and connects with bores 14c which extend crosswise near the upper side, then a portion 14d which extends downwardly at the opposite

side of its axis. Communicating with these bores 14b, 14c and 14d are forwardly extending bores 14e, shown best by dotted lines in Fig. 1 of the drawings. Communicating with the bore 14b at its lower end in said manifold is an air conductor 20 which extends to the outside of said casing and connects with another air conductor 20a in which is mounted an air valve 20b for regulating the flow of air through the bores in said manifold.

10 This manifold is also provided with another bore 19a which connects at its upper end with a bore 14f in said manifold and at its lower end connects with a large bore 19b in which is mounted a conductor 19 which is provided with conductors which extend into separate oxygen and acetylene supply and each is provided with a valve for regulating the flow of the oxygen and acetylene and their relative quantities. Extending forwardly of the main portion of the manifold 14 is an externally threaded portion 14g which is adapted to receive the large end of the hood 15 and which is threaded for securing thereto. Extending forwardly from the portion 14g is a tapered portion 14h in which the bore 14f is centrally positioned. Mounted in this bore 14f is a wire guide 3 which is secured in the manifold and is provided on its extended end with an enlarged nozzle portion 16 which is tapered, as shown best in Fig. 1 of the drawings, and provided with a series of small bores 16a, as shown best in Figs. 1, 3 and 6 of the drawings. This extended portion of the member 16 abuts rigidly against the extended end of the tapered portion 14h and is fitted so as to provide a tight fit between the two members. The member 3 is provided with a nut 4a which is adapted to draw the member 3 so that the member 16 rests against the extended end of the member 14h so that there is no chance for leakage between these members 15 and 16. The member 16 is provided with a plurality of air conducting grooves 16b in its outer surface.

The hood 15 is so arranged over the member 14h that space is provided the full length of the hood 15 to permit air from the bores 14e to pass in said space to the grooves 16b. Mounted over the extended end of the hood 15 is the nozzle cap 17 which has a conforming taper internally with the member 16 and is screw threaded internally adapted to fit on the screw threaded end of the member 15, thus providing a tight fit between the nozzle cap 17 and the nozzle member 16. The guide 3 is provided with a central bore adapted to guide the wire W as it moves forwardly to the nozzle. Mounted in alignment with this guide 3 is another guide 4 in the opposite side of the box 1 which extends outwardly and serves as a guide for the wire W, it being noted that there is a space where the wire is not guided on the interior of the box 1 where it is supported between the rolls 5 and 6.

The apparatus is supported upon an arm member 18 secured on the lower face of the manifold 14 which is provided with a backwardly extending arm for guiding and shifting the apparatus which is mounted on a ball joint 18a which may be positioned in any kind of a socket so that the device may be shifted to various positions by means of the member 18.

70 The operation of the apparatus is as follows: Wire of the desired nature is fed through the guides 3 and 4 by means of the rolls 5 and 6 and their operating mechanism at the desired speed. Oxygen and acetylene is conducted through the bores 19a, regulated by the valves

in the proper proportions and quantities to the bore 14f, then through the portion 16a and as it passes out of the end of the nozzle 16 is burned and melts the end of the wire. As this wire is melted, air passes through the valve 20b and conductors 20a, 20, 14b, 14c, 14d and 14e, then between the members 14h and 15 and through the grooves 16b and carries the melted or fused portion of the wire in spray form on to the surface to be built up.

10 It will be noted that the air from its entrance into the device to its exit is entirely separate from the fuel consisting of oxygen and acetylene, so that there is no leakage from one to the other.

15 Though we have shown and described a particular construction, combination and arrangement of parts and portions, we do not wish to be limited to this particular construction, combination and arrangement but desire to include in the scope of our invention the construction, 20 combination and arrangement substantially as set forth in the appended claims.

Having thus described our invention, what we claim as new and desire to secure by Letters Patent is:

1. In a metal spraying apparatus, a gear casing, wire feeding means positioned in said gear casing, a single piece manifold secured in the one side of said gear casing and provided with a forwardly extending tapered contracted portion extending to near the nozzle end of said spraying apparatus and provided with separate fuel and air conducting conduits in said manifold, a wire guide mounted in said manifold and extending through said contracted extended portion and provided with an integral nozzle on its one end adapted to seat against the extended end of said contracted portion and its other end extending into said gear casing, a nut on said wire guide in said gear casing for drawing the nozzle end of said wire guide against the extended end of said manifold, a fuel conduit in said manifold its inner wall formed by the exterior surface of said wire guide, its one end communicating with the fuel conduit in said manifold and its other end communicating with a plurality of fuel conduits in the nozzle end of said wire guide, air conduits outwardly of said fuel conduits in said nozzle end of said wire guide and communicating with the air conduits in said manifold, and a hood secured to said manifold and extending in spaced relation over said extended portion of said manifold forming an air conduit with said extended portion.

2. In a metal spraying apparatus, a gear casing, wire feeding means positioned in said gear casing, a single piece manifold secured in the one side of said gear casing and provided with a forwardly extending tapered contracted portion extending to near the nozzle end of said spraying apparatus and provided with separate fuel and air conducting conduits in said manifold, a wire guide mounted in said manifold and extending through said contracted extended portion and provided with an integral nozzle on its one end adapted to seat against the extended end of said contracted portion and its other end extending into said gear casing, a nut on said wire guide in said gear casing for drawing the nozzle end of said wire guide against the extended end of said manifold, a fuel conduit in said manifold its inner wall formed by the exterior surface of said wire guide, its one end communicating with the fuel conduit in said manifold and its other end communicating with a plurality of fuel con- 70

duits in the nozzle end of said wire guide, air conduits outwardly of said fuel conduits in said nozzle end of said wire guide and communicating with the air conduits in said manifold, a hood 5 secured to said manifold and extending in spaced relation over said extended portion of said manifold forming an air conduit with said extended portion, and an air directing cap secured over the extended end of said hood and in engagement 10 with the outer surface of the nozzle end of said wire guide.

3. In an apparatus of the class described, a wire guiding member provided with a central bore for guiding a wire, a manifold in which said wire 15 guiding member is mounted, said manifold being

provided with a portion spaced from said wire guiding member, said space forming a fuel conductor, the inner wall of which is formed by said wire guiding member, said wire guiding member provided with an integral nozzle with a plurality 5 of tapered bores therein intersecting said fuel conductor, a plurality of air conducting portions outwardly therefrom in said nozzle, a hood secured to said manifold and a portion spaced therefrom forming an air conductor and a cap 10 secured to the extended end of said hood and extending over said nozzle and extending past the end thereof.

THOMAS G. VALENTINE.
